UNITED STATES PATENT OFFICE

CLEMENT BOOTH, OF CINCINNATI, OHIO, ASSIGNOR TO CINCINNATI GRINDERS INCORPORATED, OF CINCINNATI, OHIO, A CORPORATION OF OHIO

VALVE GRINDER

Application filed July 13, 1928. Serial No. 292,456.

This invention relates to improvements in grinding machinery and more particularly to machinery particularly adapted for use in the grinding of headed articles such as 5 mushroom type automobile valves.

One of the principal objects of the present invention is the provision of a machine for the formation of valve seats or like articles which will eliminate the necessity of chucking the article prior to grinding and which will at the same time insure a more accurate concentricity of stem and seat surfaces than has been hitherto commercially attainable by the use of the prior art manufacturing 10 methods and mechanisms.

A further object of the invention is the provision of a machine for formation of a ground surface on a headed member or the like in definite concentric relation to a previously formed stem surface thereon.

Another object of the invention is the provision of a machine which shall be substantially automatic in operation and which will require minimum time and effort on 25 the part of the operator in properly positioning the work within the machine, clamping, releasing and ejecting the work, thus reducing idle time of the machine to a minimum and increasing the productivity there- 30 of.

Other objects and advantages of the present invention should be readily apparent by reference to the following specification taken in conjunction with the accompanying 35 drawings forming a part thereof and it will be understood that any modifications in structural details or combination of parts as hereinafter described within the scope of the appended claims may be made without departing from or exceeding the spirit of 40 the invention.

Figure 1 is a front view of the machine embodying the invention.

Figure 2 is a plan view thereof.

Figure 3 is a section on line 3-3 of Figure 1.

Figure 4 is an enlarged elevation of the work supporting and controlling members as from the position 4-4 indicated in Figure 2.

Figure 5 is a fragmentary sectional view through one of the control cams taken on line 5-5 of Figure 3.

Figure 6 is a vertical section through the work stem engaging mechanism as on line 6-6 of Figure 4.

Figure 7 is a similar view showing the manner of retension of the work.

Figure 8 is a fragmentary section through the grinding wheel spindle and grinding 60 wheel on line 8-8 of Figure 2.

Figure 9 is a section through the work end engaging member on the line 9-9 of Figure 4.

Figure 10 is a fragmentary section on line 65 10-10 of Figure 4.

Figure 11 is a view similar to Figure 4 illustrating a slightly modified work holding mechanism.

Figure 12 is a plan view of said mech- 70 anism.

Figure 13 is an end elevation of the mech- anism shown in Figures 11 and 12.

Figure 14 is a transverse vertical section 75 on line 14-14 of Figure 12.

Figure 15 is a fragmentary view in elevation of one of the control mechanisms, as seen from line 15-15 on Figure 13.

Figure 16 is a fragmentary sectional view 80 of a modified form of work rest blade.

In the drawings the numeral 20 designates a suitable grinding machine bed provided with the longitudinally extending ways 21 for the main slide 22 capable of being secured in adjusted position on the bed as by 85 clamps 23. Mounted on this slide is the supplemental slide 24 bearing the regulating wheel drive unit 25 which may be of conventional centerless type and includes an angularly adjustable bracket member 26 90 bearing a regulating wheel 27 rotatable at a slow speed in a clockwise direction when viewed from the front of the machine. In the form of invention illustrated the bed 20 is shown as formed with an upstanding 95 bracket 28 rotatably supporting adjusting screw 29 bearing pilot wheel 30. This screw is engaged in the swivel sleeve 31 carried by unit 25 with the result that rotation of the screw will impart in and out movement to 100

the unit 25 either with respect to the slide 22 in the event that slide 22 is clamped to the bed or carrying with it slide 22 in the event that the regulating wheel unit is locked to 5 said slide by its clamps 32 and the clamps 23 are released. In normal operation the two slides are locked together as a unit for joint in and out movement.

In addition to the initial position adjustment 10 effectable by rotation of screw 29 and in-feed movement of prescribed amount may be effected by oscillation of sleeve 31 which, for this purpose, is provided with the elongated actuating handle 33.

15 This handle also serves for actuation of the work clamping and ejecting mechanism as will be hereinafter described.

It is to be understood that the present machine while not of conventional centerless 20 type operates in accordance with certain underlying principles normally utilized in conjunction with such machines. As previously mentioned the present machine is particularly adapted for the grinding of the 25 head portions of articles such as the mushroom type valve customarily employed in internal combustion engines. Such a work piece is shown in the drawings comprising a stem portion 34 and head 35 which latter 30 is designed to have produced thereon the seating face 36. In the use of such an article the stem is the determining factor as to ultimate position of the valve since the stem slides in elongated guide sleeve or the like of 35 the engine. It is therefore desirable to first form the stem as by grinding in a centerless grinder to determine its ultimate cylindrical form and axis. The stem having been so formed it may then desirably be mounted on 40 an angle top work rest blade 37 carried by a bracket 38 on slide 22 and the regulating wheel unit 25 adjusted in proper position to engage the work piece on rest 37 when the two slides are locked together in unitary relationship. To retain the work in position 45 on the machine use is made of suitable work clamping members such as the rollers 39 shown in the drawings, said rollers being carried by suitable pivoted supports. In 50 Figure 4 of the drawings these supports are shown as individual for the respective rollers while in Figure 11 a single support with special compensating bearing for insuring uniformity of roller pressure on the work is utilized.

55 Referring to the first mentioned type the work rest bracket 38 is provided with the trunnion lugs 40 bearing the pivots 41 for the individual arms 42 having their lower 60 end urged outwardly as by springs 43 to press the respective rolls 39 thereon into engagement with the work piece stem as it will be best understood by reference to Figure 7. It will thus be seen that when the 65 rollers are in engagement with the work,

the work is urged downward into the trough between the work rest and the regulating wheel and held in intimate contact with the regulating wheel while the upward movement of the regulating wheel with respect to 70 the work rest will impart a proper and controlled rotation to the work.

In order that the work pieces may be uniform in length from the tappet engaging 75 end of the valve to the face of the valve seat the bracket 38 is further provided with the guide portions 44 for the combined stop and ejector rod 45 whose movement in one direction may be suitably limited as by inter- 80 engagement of the actuating block 46 there- 85 on with guide 44. Block 46 may be coupled as by the intermediately pivoted lever 47 with plunger 48 urged into stop position by spring 49 but actuatable in the opposite direction by suitable mechanism such as rock arm 50 on rock shaft 51. It will be understood 90 that movement of the plunger to the left will cause a right hand movement of the ejector stop 45 considering the parts as illustrated in Figure 4, this movement tend- 95 ing to throw a work piece outward or in an axial direction off the supporting rest.

In order that the work may be retained 100 during grinding in proper position in contact with the stop 45 use is made of a work 105 head contacting roller 52 carried by arm 53 on a universal pivotal support. This 110 may be advantageously effected by the use of a pivot block 54 oscillatably secured to bracket 38 as by stud or screw 55, said block 115 having the slot 56 providing ears 57 between which arm 53 is supported on pin 58. A spring 59 urges the lower end of arm 53 outwardly to move the roller into inner work alined position while a second spring 60 urges the arm inward toward the work 120 head, thus urging the work toward ejector stop 45 as shown in Figure 4. When the work is held in position on the work rest by 125 the rollers 39 acting in opposition to and in conjunction with the work rest and regulating wheel to rotatably support the work and at the same time urge it toward the ejector stop by the roller 52 it is in the same 130 position as when the stem thereof was being ground in a centerless grinder and the actual axial relationship of the work to the machine is determined by the engagement of the regulating wheel and work rest there- 135 with and independent of the use of variable clamping jaws, rotatable chucks or collets depending on accuracy of their supporting bearings or other like structures. Conse- 140 quently the work is most accurately sup- 145 ported for rotation about a definite and un- failing axis eliminating to a maximum er- 150 rors introducible by mechanical connections or supports thereof. It can then to advan- 155 tage, have the head portion thereof, ground 160

in accurate cylindrical relationship to the pre-formed cylindrical stem surface.

For the performance of this grinding there is preferably formed on the bed the 5 diagonally extending ways 61 for slide 62 bearing the grinding wheel spindle 63 driven from a suitable source of power at a grinding rate of speed in a clockwise direction and having mounted on its inner 10 end the flange wheel clamp mechanism 64 for the cup grinding wheel 65. Suitable mechanism such as screw 66 may be utilized for in and out adjustment of the grinding wheel slide as an entirety while the spindle 15 itself is provided with the self-contained oscillator unit 67 for imparting a slight axial reciprocation to the spindle and wheel carried thereby. On account of the arrangement of the parts it will be particularly 20 noted by reference to Figure 2 of the drawings that the grinding wheel spindle is held in diagonal relationship to the bed of the machine as an entirety and that while the movement of the regulating wheel slide 25 and work supporting mechanism is parallel with the bed the oscillation of the grinding wheel is diagonally related to such feeding movement. The grinding wheel has been shown as formed with a lateral operative 30 surface as at 68 substantially parallel with the axis of the wheel and in the present instance so disposed as to form substantially a 45 degree bevel on the head 35 of the valve. In this relationship of parts the 35 reciprocation of the grinding wheel spindle will cause the operative face of the grinding wheel to have a linear traverse over the work tending to exert a self-truing effect on the wheel surface and to prevent formation 40 of scratches or the like by re-current engagement of grinding wheel and work. It will further be noted on account of the relationship of parts that the cutting action of the grinding wheel is diagonally exerted 45 against the face being ground eliminating the tendency to formation of circumferential scratches or the like by imperfections on the wheel. It will further be noted that the action of the wheel is on outer supported 50 portion of the work with the result that the pressure of the retaining rolls 39 must be sufficient to positively hold and steady the stem of the valve.

When the grinding has been completed 55 there are a number of operations to be simultaneously effected. These include a relative separation of the work and grinding wheel, a release of the lateral pressure members and a shifting of the valve head engaged 60 roller into such position that the work may be axially removed without contact therewith. These several operations in the machine shown are advantageously accomplished by a single movement of the 65 lever 33 in a direction away from the oper-

ator. As the lever is so shifted it serves to oscillate sleeve 31 thus retracting the regulating wheel unit and associated parts as respects the grinding wheel. During this movement link 69 is moved to the left as 70 shown in Figure 3 carrying with it cam 70 operating to impart movement to shift rod 71 through the medium of stirrup 72 adjustably secured thereon by wing nut 73. This motion is transmitted through the 75 oscillatable plate 74 carried by lugs 75 on bracket 38 and the bar or arm 76 thereof to the lower ends of arms 42 moving the arms inward as respects their lower ends to the position shown in Figure 6, thus laterally 80 releasing the work. At the same time arm 76 contacts with the lower end of the work terminus engaging arm 53 to correspondingly oscillate this arm and move roller 52 outward clear of the end of the work. 85

Inasmuch as it is desirable to utilize the spring pressure action of arm 53 and roller 52 in urging a new work piece toward the ejector stop 45 it has been found advantageous to oscillate arm 53 about its pivot, 90 moving roller 52 forwardly as well as laterally. This can be advantageously effected through the provision of a cam block 77 carried by bracket 38 in position to be engaged by the wedge shape stud 78 carried by 95 the lower end of arm 53 and acting in opposition to spring 60. Consequently as the lower end of the arm is swung inward member 78 riding on the incline or cam surface 79 will swing the lower end of the lever toward the rear of the machine thus moving the roller at the upper end forwardly. 100

During the time this action has been taking place pin 81 on lever 33 has been moving idly in notch or recess 82 of slide rod 83 having the pawl portion 84 for cooperation with ejector ratchet 85 for actuation of the latter. The ejector ratchet is carried by the outer or right hand end of rock shaft 51. Continued movement of cam 70 from the position shown in Figures 3 and 5 will be ineffective so far as additional actuation is considered but will merely hold the several rollers in released position while the continued movement of the lever and member 83 will serve to rock shaft 51 and thus actuate the ejector to axially force the completed and released work piece from the machine. It is then merely necessary for the operator to insert a new work piece and 110 reverse the shift lever 33 when the work will be automatically clamped in proper position and then advanced into engagement with the grinding wheel. 115

Figures 11 to 15 inclusive illustrate certain alternative mechanism for actuation of the work engaging members. In this embodiment the work rest bracket 86 has pivoted thereto a single arm 87 provided at its upper end with a self-aligning bearing 120

88 for spindle 89 bearing the pair of work engaging rollers 90 at opposite ends thereof. This arm is actuated inward into clamping engagement with the work piece stem 34 by spring 91. Retraction of the arm for release of the work is effected through plunger 92 having the notch 93 for cam 94 on actuating rod 95. This rod slides through suitable guides 96 on bracket 86 and at its forward end is connected by link mechanism 97 with rock shaft 98 which extends to the right hand side of the machine and corresponds to shaft 51 in the previously described form of the invention.

15 Rod 95 at its rearward end is coupled through rock lever 99 with slide block 100 on ejector stop 101 normally rearwardly urged by the spring 102. Consequently as the rod is moved toward the rear by rocking of shaft 98 cam 94 will move arm 87 and rollers 90 into disengaging position and subsequently cause the ejector to throw out the completed work piece.

To hold the work inward during grinding use is made of the end contacting roller 103 corresponding to roller 52 previously described and carried by arm 104 supported for in and out swinging movement by trunnion block 105 and for lateral swinging movement in the block on pivot 106. Springs 107 and 108 normally hold roller 105 in the work engaging piston shown in Figures 11 and 12. To effect a shifting of the roller into inoperative position out of alignment with the work use is made of cam 118 on the reciprocating member 95 cooperating with anti-friction roller 109 on stud 110 carried by the lower end of arm 104. The action of this cam as it will be understood by reference to Figures 13 and 15 depresses the roller swinging the arm laterally about its pivot 106. During this lateral swinging movement adjustable cam screw 111 will ride upwardly and outwardly on the incline face of cam 112 thus causing a forward as well as lateral movement of roller 103 so that on its return movement it will properly come up against the head of a new work piece and push the work piece in against the ejector stop, functioning therefore in the same manner as roller 52 of the other form of invention.

It will thus be seen that in both forms of the invention there has been provided an improved automatic work retaining and releasing means for positively laterally urging and clamping the stem of a work piece in rotary engagement with a regulating wheel for controlling the rotation of the work and for axially urging the work against a definite stop and in the direction of the grinding wheel operating on a portion of the work distant from the regulating wheel.

It will further be noted that the actuation or retention of the work is preferably

by resilient or yielding means allowing the work to automatically adjust itself in position within the machine and preventing jam or breakage of parts in the case of over size work pieces as respects either length 70 or diameter.

In addition it will be noted the several work engaging members are so inter-connected with the feed control mechanism of the machine as to properly engage and hold the work during the feeding movement and to automatically release and discharge the work on relative separation of the work and grinding member.

In the modified form of work rest blade 80 shown in Figure 16 the work rest blade 120 is provided with a concaved portion 121 to receive the stem portion 122 of the work piece. It has been found in practice that if the stem 122 had chattered while being ground, the concaved portion 121 will span the portions of the stem between successive chatter marks and prevent said chatter marks from being transmitted to the enlarged portion or seat of the work piece 85 while said enlarged portion or seat is being ground.

I claim:

1. A grinding machine including a work rest and a regulating wheel disposed adjacent thereto and operable at a slow work controlling rate of speed, means disposed in opposition to the regulating wheel for urging a work piece on the rest into engagement with said wheel means laterally displaced as respects said regulating wheel for grinding a projecting terminal portion of the work piece, a stop for limiting axial movement of the work, and means for urging the work toward the stop during the grinding operation.

2. A grinding machine including a work rest and a regulating wheel disposed adjacent thereto and operable at a slow work controlling rate of speed, means disposed in opposition to the regulating wheel for urging a work piece on the rest into engagement with said wheel, means laterally displaced as respects said regulating wheel for grinding a projecting terminal portion of the work piece, a stop for limiting axial movement of the work, means for urging the work toward the stop during the grinding operation, and a single actuating means for moving the lateral and axial work engaging members into inoperative position.

3. A grinding machine including a work rest and a regulating wheel disposed adjacent thereto and operable at a slow work controlling rate of speed, means disposed in opposition to the regulating wheel for urging a work piece on the rest into engagement with said wheels, means laterally displaced as respects said regulating wheel for grinding a projecting terminal portion of the work piece.

- the work piece, a stop for limiting axial movement of the work, means for urging the work toward the stop during the grinding operation, and a single actuating means for moving the lateral and axial work engaging members into inoperative position, and connections between said means and the work stop for ejecting the released work piece. 5
4. A grinding machine including a work support and a regulating wheel disposed adjacent thereto, means for laterally urging the work on the support in the direction of the regulating wheel, means for limiting axial movement of the work on the support in one direction, means for urging the work in said axial direction, and means for imparting a combined lateral and axial disengaging movement to said work urging means. 10
- 20 5. A machine for the formation of a conical surface on a headed member including means for supporting and rotating the member by the shank thereof, a grinding member disposed adjacent said work supporting means having a grinding surface disposed at an angle to the shank to produce the desired conical surface, and means for terminally engaging the work piece to axially urge same in the direction of the grinding wheel.
- 25 6. A machine for the formation of a conical surface on a headed member including means for supporting and rotating the member by the shank thereof, a grinding member disposed adjacent said work supporting means having a grinding surface disposed at an angle to the shank to produce the desired conical surface, means for terminally engaging the work piece to axially urge same in the direction of the grinding wheel, and means for imparting relative feeding movement to the grinding wheel and work independent of said axial urge. 30
- 40 7. A machine for the formation of a conical surface on a headed member including means for supporting and rotating the member by the shank thereof, a grinding member disposed adjacent said work supporting means having a grinding surface disposed at an angle to the shank to produce the desired conical surface, means for terminally engaging the work piece to axially urge same in the direction of the grinding wheel, means for imparting relative feeding movement to the grinding wheel and work independent of said axial urge. 45
- 50 8. A machine of the character described including a work rest and a regulating wheel disposed adjacent thereto, means for laterally urging the work toward the regulating wheel, additional means for axially urging the work on the work rest, a grind-
- ing wheel, means for imparting a relative feeding and retracting movement to the work supporting mechanism and grinding wheel, and means for automatically releasing and ejecting a work piece on the relative 70 retracting movement of the parts. 5
9. A machine for the grinding of a headed article including a work rest for lateral engagement with the periphery of the stem portion of the work piece, a regulating wheel adjacent the work rest for progressive peripheral engagement with the work piece stem, means for pressing the stem on the rest into engagement with the regulating wheel, a terminal work engaging member, means for urging said member laterally toward the work piece, additional means for urging the member in a direction lengthwise of the work piece, and means for imparting a compound releasing movement to said work terminal engaging member to release the axial urge thereof against the work piece and laterally displace same as respects the work piece. 80
- 20 10. A machine for the production of a tapered surface of revolution on a work piece including means supporting the work piece for axial rotation, a cylindrical grinding wheel disposed for tangential engagement with the surface of revolution being produced on the work piece and means for imparting relative feeding movement to the work piece and grinding wheel. 90
- 25 11. A machine for the production of a tapered surface of revolution on a work piece including means supporting the work piece for axial rotating, a cylindrical grinding wheel disposed for tangential engagement with the surface of revolution being produced on the work piece, means for imparting relative feeding movement to the work piece and grinding wheel, said means shifting the work piece transverse to the axis thereof. 100
- 30 12. A grinding machine including a regulating wheel operable at a slow work controlling rate of speed, a work rest blade adjacent the regulating wheel, the work rest blade having a concaved seat therein to receive a work piece, the work piece extending beyond the work rest blade at one end, and a grinding wheel disposed in opposition to the regulating wheel and work rest blade to operate on the portion of the work piece which overhangs the work rest blade and having its axis of rotation parallel to the portion of the work piece being operated upon. 110
- 35 13. A machine for the production of frustum conical work piece surfaces including means supporting a work piece for rotation about the axis thereof, a frusto conical grinding wheel, means supporting the grinding wheel with the work contacting side thereof normal to the axis of the 120
- 40 45 50 55 60 65 70 75 80 85 90 95 100 105 110 115 120 125

work, and means for imparting a relative feeding movement to the work and grinding wheel in the direction of said portion of the grinding wheel whereby the grinding wheel will continuously engage the work in a given plane irrespective of the surface wear of the parts.

14. A machine for the production of frustum conical work piece surfaces including means supporting a work piece for rotation about the axis thereof, a frusto conical grinding wheel, means supporting the grinding wheel with the work contacting side thereof normal to the axis of the work, means for imparting a relative feeding movement to the work and grinding wheel in the direction of said portion of the grinding wheel whereby the grinding wheel will continuously engage the work in a given plane irrespective of the surface wear of the parts, said grinding wheel having a peripheral operative portion at an angle to the frustum conical surface thereof for tangential engagement with the work piece at an acute angle to the axis of rotation thereof.

15. A machine for the production of frustum conical work piece surfaces including means supporting a work piece for rotation about the axis thereof, a frusto conical grinding wheel, means supporting the grinding wheel with the work contacting side thereof normal to the axis of the work, means for imparting a relative feeding movement to the work and grinding wheel in the direction of said portion of the grinding wheel whereby the grinding wheel will continuously engage the work in a given plane irrespective of the surface wear of the parts, said grinding wheel having a peripheral operative portion at an angle to the frustum conical surface thereof for tangential engagement with the work piece at an acute angle to the axis of rotation thereof, and means for imparting relative reciprocation to the work and grinding wheel along their common line of tangency.

16. A machine for the centerless grinding of seats on mushroom valves or the like including a work support, a regulating wheel disposed adjacent the work support for cooperative engagement with a work piece stem, means for holding the work in intimate engagement with the rest and regulating wheel, an angularly disposed grinding wheel adjacent said parts for operative engagement with an overhanging head on the work piece stem the angle of rotation of the grinding wheel to the said adjacent parts corresponding to the ground surface to be formed on the work piece and means for axially urging the work on its support in the direction of the grinding wheel to secure proper operative engagement between the work and grinding wheel.

17. A machine for the centerless grinding of seats on mushroom valves or the like including a work support, a regulating wheel disposed adjacent the work support for cooperative engagement with a work piece stem, means for holding the work in intimate engagement with the rest and regulating wheel, an angularly disposed grinding wheel adjacent said parts for operative engagement with an overhanging head on the work piece stem, the angle of rotation of the grinding wheel to the said adjacent parts corresponding to the ground surface to be formed on the work piece, means for axially urging the work on its support in the direction of the grinding wheel to secure proper operative engagement between the work and grinding wheel, and a release mechanism for disassociating the several work urging members from the work piece to facilitate removal and replacement thereof.

18. A machine for the centerless grinding of seats on mushroom valves or the like including a work support, a regulating wheel disposed adjacent the work support for cooperative engagement with a work piece stem, means for holding the work in intimate engagement with the rest and regulating wheel, an angularly disposed grinding wheel adjacent said parts for operative engagement with an overhanging head on the work piece stem, means for axially urging the work on its support in the direction of the grinding wheel to secure proper operative engagement between the work and grinding wheel, and a release mechanism for disassociating the several work urging members from the work piece to facilitate removal and replacement thereof, said mechanism including means for automatically laterally displacing the axial work urging means.

19. In a machine of the character described, the combination with a work rest or support of a regulating wheel disposed adjacent thereto and operative at a slow work controlling rate of speed, means in opposition to the regulating wheel for urging a work piece on the support into frictional engagement therewith and prevent tilting of the work, a grinding wheel disposed adjacent the parts for engagement with a projecting portion of a work piece, means removed from the work support for urging the work axially in the direction of the grinding wheel to insure proper grinding thereof, an ejector adjacent the work support, means for imparting relative transverse feeding movement to the grinding wheel and work, and operating mechanism for the several parts adapted to actuate the several mechanisms aforesaid to successively clamp and axially urge the work, operatively associate the work and grind-

ing wheel, disengage the parts, release the work and eject same substantially as described.

20. In a grinding machine for grinding 5 tapered faces on headed articles comprising a work rest blade for supporting the stem of a work piece, a regulating wheel disposed adjacent the work rest blade for engagement with the work piece stem to position same on the work rest blade and control rotation thereof, the work rest blade and regulating wheel forming a work receiving trough, means for steadyng the work piece within the trough, and a grinding wheel having its axis of rotation disposed at an angle to the axis of rotation of the work piece, the angle between the axes of rotation of the grinding wheel and work piece corresponding to the angle of the 10 tapered face to be formed on the said work piece.

21. A machine for the centerless grinding 15 of seats on mushroom valves or the like including a work positioning blade and a pair of work positioning rollers located on opposite sides of the blade, means for varying the relative separation of said three parts to clamp or release a valve stem in the throat formed by said parts, means for 20 positively rotating one of said members whereby a frictional rotative movement is imparted to a work piece when held between said parts, and a grinding member disposed adjacent said work holding fixture for operative engagement with a projecting portion of a retained work piece.

22. A machine for the centerless grinding 25 of seats on mushroom valves or the like including a work positioning blade and a pair of work positioning rollers located on opposite sides of the blade, means for varying the relative separation of said three parts to clamp or release a valve stem in the throat formed by said parts, means for 30 positively rotating one of said members whereby a frictional rotative movement is imparted to a work piece when held between said parts, a grinding member disposed adjacent said work holding fixture for operative engagement with a projecting portion of a retained work piece, and means for varying the relationship of the grinding wheel and fixture to effect desired stock removal from the work piece.

23. A machine for the centerless grinding 35 of seats on mushroom valves or the like including a work positioning blade and a pair of work positioning rollers located on opposite sides of the blade, means for varying the relative separation of said three parts to clamp or release a valve stem in the throat formed by said parts, means for 40 positively rotating one of said members whereby a frictional rotative movement is imparted to a work piece when held be-

tween said parts, a grinding member disposed adjacent said work holding fixture for operative engagement with a projecting portion of a retained work piece, and means terminally engaging a restrained work 70 piece for limiting its axial movement with respect to the fixture in the direction of the grinding wheel.

24. A machine for the centerless grinding 75 of seats on mushroom valves or the like including a work positioning blade and a pair of work positioning rollers located on opposite sides of the blade, means for varying the relative separation of said three parts to clamp or release a valve stem in 80 the throat formed by said parts, means for positively rotating one of said members whereby a frictional rotative movement is imparted to a work piece when held between said parts, a grinding member disposed adjacent said work holding fixture for operative engagement with a projecting portion of a retained work piece, means terminally engaging a restrained work piece for limiting its axial movement with respect to the 85 fixture in the direction of the grinding wheel, means for releasing the clamping engagement of the rollers and work supporting blade on the work piece, and means for effecting an axial ejection of the work 90 piece when released.

25. A machine for the centerless grinding 95 of an annular surface on a headed cylindrical article or the like including a rigid work rest blade for engagement with the stem 100 portion of the article, a regulating wheel and movable lateral supports such as rollers disposed on opposite sides of the work rest blade, one of said three parts being shiftable with respect to the other two to restrict 105 the throat, to secure a work piece against tilting relative thereto during grinding with the portion thereof to be ground projecting beyond the throat, means for rotating the regulating wheel at a slow rate of speed to 110 frictionally control the rate of rotation of the work, and a grinding member disposed exterior to the throat and with its axis angularly disposed with respect thereto for presentation of the grinding wheel in proper 115 operative relation to the projecting portion of the work to be ground.

In testimony whereof I affix my signature.
CLEMENT BOOTH.
